Ida Garnetz, INVENTOR

BY Victor J. Evans & Co.

ATTORNEY

UNITED STATES PATENT OFFICE

IDA GARNETZ, OF WATERFORD, WISCONSIN

CURTAIN ROD THREADER

Application filed February 17, 1932. Serial No. 593,632.

My present invention has reference to an article for housewives use, and is in the nature of a threader of a construction to firmly grip the ends of either round or rectangular curtain rods to permit of the same being threaded through the loop at the top of a conventional fabric curtain to facilitate such operation and to prevent the cutting or tearing of the curtain by the sharp edges of the rod.

To the attainment of the foregoing the invention consists in the improvement hereinafter described and definitely claimed.

In the drawing:

Figure 1 is a perspective view illustrating the application of the improvement.

Figure 2 is an approximately central transverse longitudinal sectional view through the improvement with the round rod gripped therein.

Figure 3 is a side elevation of the improvement with parts broken away.

Figure 4 is a transverse sectional view on the line 4-4 of Figure 3.

Figure 5 is a similar sectional view but illustrating the jaw end of the threader engaging with the grooved and substantially rectangular curtain rod.

It will be noted as the description progresses that the improvement is of an extremely simple construction which may be cheaply manufactured and commercialized. The threader is constructed of a single piece of any desired material that embodies resiliency and the said threader 1 is substantially elliptical in cross section and is tapered from one to its other or pointed end 2. The end 2 is rounded, as is the body of the device so that no sharp or abrupt surfaces are presented. The outer and widened end of the body 1 is slotted longitudinally for a determined portion of its length to provide oppositely arranged spring clamping jaws 3 and 4, respectively. The inner faces of the jaws 3 and 4 are rounded outwardly at the ends thereof so that there is a flared opening or mouth between the jaws.

The jaws have their confronting faces centrally grooved longitudinally, as at 5, and the said grooves have inner rounded walls.

The inner or active face of the jaw 4 is cut at opposite inward angles from its outer end to the groove 5 therein to provide the same with angle walls 6.

A round curtain rod 7 is inserted through the flared opening between the jaws and is received in the grooves 5 and firmly held in position by the spring tension of the jaws toward each other. The rod 7 may be readily fed through the fold 8 of a curtain 9 as disclosed by Figure 1 of the drawing without liability of injury to the curtain, which is very liable to occur when the abrupt end of the rod 7 contacts with the cloth or with the threads when the rod is fed through the fold 8 without the improvement thereon. The rod can be expeditiously fed through the fold 8.

When cross sectionally rectangular curtain rods 9' are employed, such rods are directed between the inner faces of the jaws. This type of rods have their edges rounded and bent at outward angles, as at 10, in order to permit of the cooperating rod section telescoping therein and the feeding of this type of rods through the fold of a curtain requires extreme care unless a threader attachment is applied. The walls 10 of the rod 9' contact with the angle walls 6 on the jaw 4 of the improvement and while the jaws 3 and 4 exert a sufficient pressure against both the round type and rectangular type of rods to hold the same between the jaws such pressure is not sufficient to compress or otherwise interfere with the shape of the rods.

The construction and advantages of the improvement will, it is thought, be apparent by those skilled in the art to which the invention relates so that further detailed description will not be required.

Having described the invention, I claim:

A threading point for curtain rods, comprising a member which is substantially elliptical in cross section and which is tapered from one to its other end, and whose reduced end is rounded, said member, from its widened end being centrally slotted longitudinally for a determined length to afford opposed jaws which exert a spring tension toward each other and each of said jaws be-

ing centrally and longitudinally grooved, and being inwardly rounded from their outer ends, and the inner wall of one of the jaws being inclined from the outer edge to the 5 central groove therein, for the purpose set forth.

In testimony whereof I affix my signature.
IDA GARNETZ.
